UNITED STATES PATENT OFFICE

128,601

DESIGN FOR A BABY SANTA CLAUS DOLL

Ruth E. Chaine, New York, N. Y.

Application May 29, 1941, Serial No. 101,220

Term of patent 7 years

To all whom it may concern:

Be it known that I, Ruth E. Chaine, a citizen of the United States, residing in the Borough of Manhattan, city, county, and State of New York, have invented a new, original, and ornamental Design for a Baby Santa Claus Doll, of which the following is a specification, reference being had to the accompanying drawing, forming part thereof.

Fig. 1 is a front view of a baby Santa Claus doll embodying my new design.

Fig. 2 is a perspective view thereof.

I claim:

The ornamental design for a baby Santa Claus doll, as shown.

RUTH E. CHAINE.
